UNITED STATES PATENT OFFICE

JAMES W. NABB, OF NEWARK, NEW JERSEY, ASSIGNOR TO UNITED SHOE MACHINERY CORPORATION, OF PATERSON, NEW JERSEY, A CORPORATION OF NEW JERSEY

SHOE-PRESSING MACHINE

Application filed June 12, 1925. Serial No. 36,654.

This invention relates to shoe-pressing machines and is illustrated as embodied in a sole-laying machine of the type shown in Letters Patent No. 1,549,243, granted on August 11, 1925, upon an application of E. E. Winkley.

Machines of this type comprise a sole-pressing pad and a shoe-supporting jack provided with a heel post having a pin or 10 spindle to enter the thimble of the last of the shoe to be operated on, and a toe post having an upper-engaging member ordinarily comprising a roll journaled on the toe post. As heretofore constructed, this roll has been 15 formed of rubber arranged to engage the top of a shoe upper substantially at the toe or between the toe and the instep. The rubber surface of the roll gradually deteriorates in use, becoming rough and uneven, so that even- 20 tually it is found desirable to replace the roll in order to avoid marking or indenting the shoe uppers.

I have found that the necessity for such replacement can be largely avoided or great- 25 ly postponed by providing the roll with a cover not fastened to it but free to creep thereon as the roll is used, being held in place by frictional contact with the roll. Such a roll may be usefully employed in machines 30 such as sole-pressing machines of the type referred to for a much longer period of time than heretofore without liability of marring shoes or damaging the roll itself.

Preferably the roll-cover is made of soft 35 rubber stretched over the roll, frictional contact between the tensioned cover and the roll being depended upon, as above indicated, to hold the cover in place. As a further advan- 40 tage, such a cover is readily removable and replaceable, thus further prolonging the useful life of the roll.

Although the present invention is de- 45 scribed with particular reference to its utility in sole-pressing machines, since it was in an effort to improve the organization of such machines that the invention was developed, it should be understood that in various aspects the invention is not so limited, but may 50 be employed to advantage in connection with

shoe-engaging or supporting members of machines other than sole-pressing machines.

These and other features of the invention, including certain details of construction and combinations of parts, will be described as 55 embodied in an illustrative machine and pointed out in the appended claims.

In the drawings,

Fig. 1 is a front elevation showing those parts of the machine which are necessary to 60 an understanding of the present invention.

Fig. 2 is a cross-section of the toe roll with its cover.

Fig. 3 is a perspective view of the cover detached.

Fig. 1 shows the upper part of the machine only and reference may be made to the Letters Patent referred to for further details if desired. The machine shown is a twin machine and comprises a frame 10, with vertical rods 12, up and down which sole-pressing pads 14 are simultaneously and oppositely moved by a power mechanism comprising toggle links 16. The upper ends of the rods 12 support depending shoe-supporting jacks 18 having jack-pin posts 20 and toe-roll supporting posts 22. The rolls 24 are mounted at the ends of the posts 22 and are freely journaled there on horizontal axes perpendicular to the longitudinal axes of shoes in 80 the machine. The rolls 24, as shown, are formed of rubber, for example substantially as shown in United States Letters Patent No. 1,163,589, granted Dec. 7, 1915, on the application of H. A. Davenport. Each roll consists of a metal sleeve 26, surrounded by a preferably approximately cylindrical body 28 made of rubber, the exterior portion of which, at least, is rubber of medium hardness.

Each of the illustrated rolls 24 is provided 90 with a cover or sleeve 30 made of relatively thin soft rubber. For example, I have found that a piece cut from an inner tube of a motorcycle or automobile tire serves well for this purpose, although a satisfactory rubber cover 95 may be obtained in various ways. The cover 30 is slipped over the roll, being preferably of such diameter as to require a little stretching to place it in position, and being long enough to cover the length of the roll.

The use of this cover avoids damage to the uppers of shoes treated by the machine and also to the main body of the roll, and the cover itself will wear in use many times as long as the unprotected roll. The tensioned cover, being held in place only by friction between it and the roll, creeps on the roll, in use, to some extent, thereby relieving the surface stresses between the shoe and the roll, especially in the direction of the axis of the roll or in directions tangential to the roll. Also, the described mounting of the cover allows it to stretch somewhat, which appears to contribute to the usefulness of the cover. The illustrated machine is used in exactly the same manner as the machines disclosed in the Letters Patent referred to, and no detailed exposition of such use is necessary herein.

The "rolls" above described are rolls only in form. They are really only contact members or supports, and do not rotate in any definite way during the pressing operation on a shoe. They do move enough so that, in time, they distribute the wear over their whole surfaces, but this movement is adventitious and small or even nothing during any few-minute period. The invention should not be understood as limited to a "roll", or cylindrical contact member, as it is useful with contact members of other forms.

Having described my invention, what I claim as new and desire to secure by Letters Patent of the United States is:

1. A sole-pressing machine having, in combination, a sole pressing pad, and a shoe upper engaging member provided with a cover arranged to creep on the said member under the pressure of the shoe upper.
2. A sole-pressing machine having, in combination, a sole pressing pad, and a shoe-supporting jack comprising a shoe upper pressing member provided with a relatively thin rubber cover frictionally held on the pressing member and arranged to move relatively to the pressing member under tangential stress.
3. In a sole-pressing machine having a sole pressing pad, a shoe-supporting jack comprising a toe post and a roll journaled thereon and provided with a rubber tube of somewhat smaller normal diameter than the roll stretched over the roll and arranged to engage the upper of a shoe and to creep on the roll under stresses tangential to the roll.
4. A toe roll for a sole-pressing machine having a soft rubber cover stretched over it, and arranged to creep under stresses tangential to the roll.
5. In a machine for operating on boots and shoes, a shoe-treating member, and shoe-supporting means comprising a member arranged to engage the top of the forepart of the shoe and provided with a tensioned cover frictionally held in place on said member, while capable of creeping thereon in response to pressure of the shoe against it.

6. In a machine for operating on boots and shoes, a shoe-treating member, and shoe-supporting means comprising a member provided with a tensioned, relatively thin rubber cover frictionally held in place on said member but free to creep and stretch to avoid marring the shoes treated. 70

7. In a sole-pressing machine having a sole pressing pad, a shoe-supporting jack comprising a heel post, a toe post, and a roll journaled on the toe post and having a shoe upper engaging cover of soft rubber tensioned to hold the cover frictionally on the roll. 75

In testimony whereof I have signed my name to this specification. 80
